UNITED STATES PATENT OFFICE.

SMITH SKINNER, OF LOWELL, MASSACHUSETTS, ASSIGNOR TO WM. H. SKINNER AND JACOB NICHOLS, JR.

WASHING-MACHINE.

Specification of Letters Patent No. 18,489, dated October 20, 1857.

To all whom it may concern:

Be it known that I, SMITH SKINNER, of Lowell, in the county of Middlesex and Commonwealth of Massachusetts, have invented a novel and useful Washing-Machine; and I hereby declare the following specification, in connection with the accompanying drawings and reference thereon, constitute a lucid, clear, and exact description of the construction and use of the same.

In referring to the said drawings, Figure 1 denotes a plan or top view. Fig. 2, a side elevation of the same. Fig. 3, an end elevation of it. Fig. 4, a longitudinal and vertical section on line A, B, of Fig. 1, showing the slats of the wash board all tipped one way by the pressure of the clothes and movement of the rubber. Fig. 5, denotes a transverse and vertical section 20 of a portion of the rubber, on line C, D, Fig. 1. Fig. 6, a section of the wash board showing the slats therein tipped back by the clothes and rubber, or in a different direction from that indicated in Fig. 4. Fig. 25 7, is an under side view of the rubber and its serrated sections.

The nature of my invention consists in my within described wash board so constructed that the tipping elliptical slats in 30 the board have a movement, or tip back and forth on pivots in the center of their ends, so that by the movement and pressure of the clothes upon them they will tip the clothes first being pressed against their flat 35 surfaces, and by a continuous movement are broke on or crimped down over the sharpest edges of the slats so as to effectually wash them, and the same effect is imparted to the clothes whether they be moved in either direction on the board. And my invention 40 further consists in the rubber so constructed with serrated sections pressing downward independently of each other, and to swing or move above the wash board in the within 45 described manner as to bring the serrated surfaces in contact with every portion of the clothes, with an equal elastic pressure, in order to evenly and efficiently wash them without unnecessary wear, in the manner 50 hereinafter fully set forth.

Construction.—In order to enable persons skilled in the art to which my invention appertains to construct, use, and carry out the same I will describe it as follows: I 55 construct a box of wood seen at A, which

is water tight. In this box I fasten two cross bars seen at B, which support the wash board C in the desired position. This board is constructed of wood, the two sides being seen at D, and the end pieces at E. I construct a number of slats or ridges of an elliptical form, as seen at F, and on their ends I form round pivots seen at a, Fig. 1.

These pivots are properly fitted to holes formed in the inner portion of the sides D, 65 so that they may tip freely therein. Two holes are formed through each of these slats F, one near each end, seen at e, Figs. 4 and 6. Through these holes there are wires, seen at G, Figs. 1, 4 and 6, passed and each 70 of their ends are confined firmly to the end pieces E of the wash board C. These holes e and wires G govern the amount which the slats F tip when the clothes H are rubbed over them back and forth, as follows: When the clothes are pushed back as 75 seen at H, Fig. 4, as the arrow points, the slats are all tripped back so as to bring their flat rather than their sharp surfaces in contact with the clothes when the greatest 80 pressure is upon them, and allows the sections of the rubber to break or crimp the clothes down over the sharpest edges of the slats when the clothes are moved in either 85 direction by reason of the tipping of these slats, and they tip until the surfaces i of the holes e, through the slats, come in contact with the surfaces n of the rods or wires G which will stop their tipping.

When the rubber and clothes are pulled 90 forward, the slats will be tipped as seen in section at Fig. 6, and bring the surfaces r of the holes e against the surfaces t of the wires G, by which the tipping is stopped in an opposite position, and for the same 95 purpose as just described, when pushing the clothes as seen Fig. 4. Thus it will be seen that the flat sides of the slats are worn, instead of the sharper edges of them, which is exactly the reverse of the ridges of all other 100 wash boards heretofore in use, for the sharp edges of them are worn out first, and besides they are held stationary, consequently are soon worn out.

When the upper surfaces of the slats of 105 my machine are worn out, they can all be changes so that their under surfaces will be uppermost, and thus a new side is given the board, and of course it will last double the ordinary length of time.

I construct a rubber of wood as follows: The main part is seen at I, to this is attached two uprights seen at J, between which is fitted and fastened a cross bar seen at K. 5 Each of the top ends of the uprights J are secured or jointed, to the end of the swinging beams L, so as to turn thereon, which beams are connected together at their rear ends by the cross beam O, and the beams 10 L are attached to the turning cross bar M, which turns freely by its pivots Q, in the tops of the posts N, which are attached to the box A. To the cross beam O, I attach a weight seen at P, by means of the rod R. 15 This weight operates upon the beams O and L and rubber I connected to them, to balance them in all positions in such a manner that if the rubber be lifted up to its highest position seen in red lines at Fig. 2, it will 20 be so held, or if it be pulled down or part way down to its lowest position, it will so remain, in fact it will remain in any adjusted position from the highest to the lowest.

The cross bar K is perforated with holes 25 U to receive the upper ends of the shafts or guides S. Their lower ends pass through larger holes V formed through the main part I. The lower end of each of these guides are attached firmly to the serrated 30 sections T, the serrations being seen at W, Fig. 4, and at Fig. 7. The serrated sections are set side by side of each other, seen at Fig. 7, the serrations in one coming opposite the ridges in the next and so on as seen at 35 Fig. 7. Spiral springs, seen at Y, are placed around and near the top of the guides S. The lower ends of these spiral springs come in contact or press against the shoulders X, formed on the guides S, while their upper 40 ends come in contact with the under side of the cross bar K, to press down each of the serrated sections independently of each other, upon the clothes H, which independent action is of the utmost consequence to 45 cause all the irregular portions of the surfaces of the clothes to be alike pressed and operated upon to wash or clean them. Thus the difficulty is overcome of giving a great pressure to the thick portion of the clothes, 50 while the thin portions receive no pressure at all as in the old way, besides a great amount of unnecessary wear to the clothes, which will be readily seen.

The guides S and serrated sections T are 55 prevented from dropping down too far by the stop pins A² in the guides, which strike against the top of the main part I. Two end pieces, seen at D², are fastened to the under

ends of the main part I, of the rubber, between which the serrated sections move and 60 by which they are guided and prevented from turning when moved for use or in operation.

Operation: It will be seen that the wash board is of a segmental form or concave 65 form on its top, and that the lower or serrated surfaces of the sections of the rubber are correspondingly convexed or rounding so as to swing or be swung parallel to the board and between which the clothes H, are 70 placed to be washed. A quantity of water is poured into the box A, as seen at B², and the clothes are placed between the rubber and wash board, and the handles C², which are fastened to the rubber I, are seized by the 75 hands of the operator and vibrated back and forth, and at the same time pressed down as much as may be desired, each of the sections T, will press down upon the portion of clothes with which it comes immediately in 80 contact with the same pressure whether the clothes underneath are higher or lower, because the sections act independently of each other which will be readily seen. The slats F, of the wash board all tip back as seen in 85 Fig. 4, when the rubber is pushed back over the clothes and board, and are all tipped forward as seen at Fig. 6 when the rubber I, is pulled forward, so as to present the flattest side or surface of the slats to the 90 clothes H.

Claims.

1. I claim the wash board constructed of a number of elliptical slats or their equivalents arranged in such a manner that they 95 may tip back and forth as the clothes H are pressed and moved on them sufficiently to present their flat, instead of their sharp surfaces to the clothes, and be prevented from tipping too far, by wire rods G which pass 100 through holes e, (of a larger size than the rods,) formed through each of the slats, essentially in the manner and for the purposes fully set forth.

2. I also claim the serrated sections T or 105 their equivalents, in the rubber, so constructed and arranged in combination with the wash board C, that they can be swung back and forth, to rub and wash the clothes, essentially in the manner and for the purposes 110 fully set forth.

SMITH SKINNER.
